UNITED STATES PATENT OFFICE.

HUBERT C. ELLIS AND NORMAN C. ELLIS, OF EVANSTON, ILLINOIS.

IRONING MACHINE.

Application filed March 18, 1926. Serial No. 95,525.

The invention relates to ironing machines and more particularly to that type in which a flat-iron is reciprocated over a fixed table under control of the operator.

5 One object of the invention is to provide a machine of this type, with improved mechanism for reciprocating an iron, which comprises the electric motor which travels with the iron.

10 Another object is to provide improved reciprocating mechanism in which simple reversible gearing is used.

Another object of the invention is to provide a machine of this character which is 15 simple in construction and is readily accessible.

Other objects of the invention will appear from the detailed description.

The invention consists in the several novel 20 features hereinafter set forth and more particularly defined by the claims at the conclusion hereof.

In the drawings: Fig. 1 is a perspective of a machine embodying the invention. Fig. 2 is a vertical section through the reversible 25 gearing. Fig. 3 is a detail section, showing the iron-lifting device. Fig. 4 is a plan view, the motor being removed. Fig. 5 is a section taken on line 5—5 of Fig. 2. Fig. 6 is a 30 section taken on line 6—6 of Fig. 4.

The invention is exemplified in a structure comprising a supporting frame which is built up of sides 10, a longitudinal member 11 and a plate having a horizontal portion forming a base 13 and a vertical portion 14 forming a back, all of which are rigidly secured together in suitable manner, to form a rigid supporting structure. An ironing-board or table 15 is supported in an elevated position by a standard 16 adjacent one end, which is provided with an angular extension 17, to support the other end, so that garments may be slipped over the table. The ironing-table is usually 45 heated by any suitable means, usually electrically, in a manner well understood in the art. A flat-iron 18, usually of sufficient weight to produce the necessary pressure for ironing, is reciprocable horizontally over the table 15 and is suspended by a universal joint 19 from an arm 20, this joint permitting the necessary freedom of movement of the iron to cause it to adapt its position to the material being ironed.

50 Arm 20 is formed on a carriage 24 which is provided with circular bearings 21 and

22 which are adapted to slide and rock on a shaft 23 which extends longitudinally across the back of the frame and is fixedly secured in sides 10 of the supporting frame. 60

The mechanism for reciprocating the carriage comprises an electric motor 25 which is fixed to a bracket 26 at the back of the carriage and is movable therewith. The shaft 27 of the motor extends downwardly 65 through a gear-housing 28 formed on the carriage, to operate reversible gearing and drive a pinion 29 which meshes with a toothed rack 30 formed on the upper portion of the stationary shaft 23. Pinion 29 is 70 enclosed in a pocket 31 formed at the rear of the carriage, and is fixed to a shaft 32 which is journalled in a bearing formed in the back of the housing 28. A bevelled friction pulley 34 is keyed to the front end of 75 the shaft 32 and engages with an upper bevelled friction pulley 35 and a lower bevelled friction pulley 36, so that pulley 34, shaft 32 and pinion 29 may be driven in opposite directions to correspondingly shift 80 the carriage and the flat-iron. Pulleys 35 and 36 are loosely mounted on the motor shaft 27, and each is confined against axial movement in the housing 28 by a collar 39. A clutch-collar 40 is slidable on shaft 27 85 between pulleys 35, 36 and is splined to said shaft, so that it will rotate therewith in any position of the collar. This collar is provided with clutch-teeth 41 to engage corresponding teeth 42 on pulley 35 to drive the 90 pinion 29 in one direction, and with oppositely facing clutch-teeth 43 adapted to interlock with clutch-teeth 44 on pulley 36 to drive the pinion 29 in the opposite direction. The collar 40 is movable into neutral position 95 between pulleys 35, 36, so that the reversible gearing will be inoperative by the shaft 27. This exemplifies reversible gearing for driving the pinion 29 to cause the carriage and the flat iron to move in opposite directions within the range provided for.

In practice, it is desirable that the reciprocating mechanism should be readily and conveniently controllable, so that the operator may start and stop the iron at any point within its range of movement in opposite directions from any point. For this purpose, a controller handle 45 is mounted to travel with the carriage and in the front end of arm 20. Said handle is fixed to a shaft 105 54 which extends backwardly through arm 20 to rotate a cam 55 which is fixed to the

rear end of said shaft. Said cam has a groove to shift and hold a lever 56 which is pivotally supported by a shaft 57 which is mounted in the housing 28 and is provided with a fork 58 which has studs 59 extending into an annular groove 60 in clutch collar 44 and whereby the collar may be shifted and held while it is rotating. The groove in the rear face of cam 55 has a concentric portion 55^a adapted to hold lever 58 in its neutral position, a portion 55^b, adapted to hold the lever so the clutch-collar will be locked to drive wheel 36 to rotate pinion 29 in one direction, a portion 55^c adapted to hold the clutch-lever so the collar will be locked to drive wheel 35 to rotate the pinion 29 in the opposite direction, and inclined portions between said holding portions, whereby the clutch-lever will be shifted from neutral to either of its other positions and vice versa. This exemplifies a clutch-controlling device for the reversible gearing which is mounted on the iron carriage and which may be conveniently manipulated to control the movement of the iron from any point within its range of travel. To automatically shift the clutch collar 40 when the iron reaches the end of its stroke in either direction, a slide 62 is slidably held by screws 63 on top of the carriage and is formed with a longitudinal slot 64 to permit limited movement of the slide relatively to the carriage. This slide is provided at its front with depending lugs 65 and 66 which are adapted to engage a stud 67 formed on cam 55 and at its rear with lugs 68 and 69 which are adapted to engage the hubs of arms 70 respectively which are disposed adjacent the frame-side 10. When the iron is travelling to the left, as the result of the shift of the handle 45 in the same direction, stud 67 will engage lug 66 and shift the slide to the left, so that, as it approaches the end of its stroke, lug 69 will strike arm 70 until the cam 55 has been shifted into its neutral position, whereupon wheel 35 will become idle, so that the iron will stop. When the iron is travelling to the right, as the result of the movement of the handle 45 in the same direction, lug 68 will engage the arm 70 at the right side of the machine as the carriage approaches the end of its stroke to shift lever 57 to operate the clutch-member 40 into neutral position and thus disconnect the driving connection for wheel 36, so that the iron will stop. This exemplifies means for automatically shifting a clutch for controlling the reversible gearing to stop the carriage at the end of its stroke.

60 Carriage 20 is preferably formed of sections 24^a, 24^b which are removably secured together by bolts 24^c, to permit the reverse gearing to be conveniently assembled and to provide access thereto whenever desired.

The housing 28 is adapted to contain lubricant for the gearing. A switch 84, for controlling the motor, may be mounted at any convenient point. Current will be supplied to the motor 25 through a flexible cord which maintains a connection between the motor and a source of current when the iron is in any of its positions.

In practice, it is frequently desirable to lift the iron over obstructions, such as buttons, on the material being ironed, without stopping the iron. To permit this to be done, provision is made whereby the operator may manually and readily lift the iron off the work and lower it. The carriage 24 is free to rock on shaft 23 for this purpose. A roller 71 is mounted on the lower end of a fork 72 projecting downwardly from the carriage. This roller is adapted to be shifted by an angle-bar 73 which extends longitudinally across the back of the frame and is pivotally suspended at its ends by arms 70 which are hung on shaft 23. Angle-bar 73 is provided with a roller 74 which is adapted to be engaged by a cam 75 on the upper end of a rod 76 which is mounted to slide vertically in guides 77. A lever 78, which is fulcrumed to the base of the frame at 79, and pivoted at 81 to rod 76 is provided at its front end with a pedal 80, by which cam 75 may be shifted at the will of the operator. A spring 81 is applied to normally hold the cam in its inoperative position. When the iron is in its working position, roller 71 will be disengaged from angle bar 73, so that the weight of the iron will be applied to the work. When the pedal 80 is depressed while the iron is in any of its positions, cam 75 will swing the angle bar 73 forwardly to swing the carriage to lift the arm 20 upwardly and lift the iron off the work. When the pedal is released, the iron will drop back onto the work. Thus, the operator may readily lift the iron off an obstruction without stopping the movement of the iron. The teeth of rack 30 are formed to permit slight relative shift of the pinion 29 without disengaging the pinion from the rack. The range of movement of the iron to the right is sufficient to permit it to travel off the ironing table and to effect automatic lifting of the iron, and to hold it supported after it passes off the table 15, a track 82 is formed adjacent one end of the angle bar 73, onto which the roller 70 will ride before the iron leaves the table 15.

120 The invention exemplifies an ironing machine in which the flat iron may be reciprocated at will of the operator by mechanism comprising reversible gearing and a motor mounted to travel with the carriage, from which the iron is suspended; which is simple in construction and efficient in operation; which is readily controllable; and in

which the iron may be manually raised to pass over obstructions on the work at the will of the operator.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In an ironing machine, the combination of a frame, an ironing table, a flat-iron mounted to reciprocate horizontally over the table, mechanism for reciprocating the iron, an electric motor mounted to reciprocate with the iron and connected to drive said mechanism, and means to control said mechanism to start and stop the iron at will at any point within its range of travel.

2. In an ironing machine, the combination of a frame, an ironing table, a flat-iron mounted to reciprocate horizontally over the table, mechanism for reciprocating the iron comprising reversible gearing, reciprocable with the iron, an electric motor connected to drive said gearing, also mounted to reciprocate with the iron, and means to control said mechanism to start and stop the iron at will at any point within its range of travel.

3. In an ironing machine, the combination of a frame, an ironing table, a vertically movable flat-iron mounted to reciprocate horizontally over the table, means for vertically shifting the iron, mechanism for reciprocating the iron, an electric motor, reciprocable and vertically movable with the iron and connected to drive said mechanism, and means to control said mechanism to start and stop the iron at will at any point within its range of travel.

4. In an ironing machine, the combination of a frame, an ironing table, a flat-iron, an arm mounted to reciprocate horizontally over the table and to swing vertically, means for swinging the arm, mechanism for reciprocating the arm, an electric motor connected to drive said mechanism and mounted to reciprocate with the arm, and means to control said mechanism to start and stop the iron at will at any point within its range of travel.

5. In an ironing machine, the combination of a frame, an ironing table, a flat-iron mounted to reciprocate horizontally over the table, mechanism for reciprocating the iron, an electric motor connected to drive said mechanism and mounted to reciprocate with the iron, means to automatically stop the iron at the end of its range of movement and means to control said mechanism to start and stop the iron at will at any point within its range of travel.

6. In an ironing machine, the combination of a frame, an ironing table, a vertically

movable flat-iron mounted to reciprocate horizontally over the table, means to vertically shift the iron, mechanism for reciprocating the iron, an electric motor connected to drive said mechanism and reciprocable and vertically movable with the iron, means for manually lifting the iron at any point within its range of travel, and means to control said mechanism to start and stop the iron at will at any point within its range of travel.

7. In an ironing machine, the combination of a frame, a carriage mounted to reciprocate horizontally in the frame, a flat-iron mounted on and to reciprocate with the carriage, reversible gearing mounted on and to reciprocate with and connected to reciprocate the carriage, means for driving the gearing mounted on and to move with the carriage, and means to control said gearing to start and stop the iron at will at any point within its range of travel.

8. In an ironing machine, the combination of a frame, a carriage mounted to reciprocate horizontally and to swing vertically in the frame, means to shift the carriage vertically, a flat-iron mounted on and to reciprocate with the carriage, mechanism for reciprocating the carriage comprising reversible gearing mounted on the carriage, and means to control said mechanism to start and stop the iron at will at any point within its range of travel.

9. In an ironing machine, the combination of a frame, a carriage mounted to reciprocate horizontally in the frame, a flat-iron mounted on and to reciprocate with the carriage, reversible gearing mounted on and connected to reciprocate the carriage, a motor mounted on the carriage and connected to drive said gearing, and means to control said gearing to start and stop the iron at will at any point within its range of travel.

10. In an ironing machine, the combination of a frame, a carriage mounted to reciprocate horizontally in the frame, a flat-iron mounted on and to reciprocate with the carriage, reversible gearing mounted on and connected to reciprocate the carriage, a motor connected to drive said gearing and mounted on and to reciprocate with the carriage, and means mounted on the carriage to control said gearing to start and stop the iron at will at any point within its range of travel.

11. In an ironing machine, the combination of a frame, a carriage mounted to reciprocate horizontally in the frame, a flat-iron mounted on and to reciprocate with the carriage, reversible gearing mounted on and to reciprocate with and connected to reciprocate the carriage, a motor mounted on the carriage and connected to drive said gearing, means to automatically stop the iron at the end of its range of travel, and means to con-

- tral said mechanism to start and stop the iron at will at any point within its range of travel.
12. In an ironing machine, the combination of a frame, a carriage mounted to reciprocate horizontally and to swing vertically in the frame, means for vertically swinging the carriage, a flat-iron mounted on and to reciprocate with the carriage, reversible gearing mounted on and connected to reciprocate the carriage, means mounted on the carriage for driving said gearing, means for manually lifting the iron at any point within its range of travel, and means to control said mechanism to start and stop the iron at will at any point within its range of travel.
13. In an ironing machine, the combination of a frame, an ironing table, a carriage mounted to reciprocate in the frame, a flat iron mounted on and to reciprocate with said carriage, mechanism for reciprocating the carriage comprising a stationary rack, a pinion mounted on the carriage and engaging the rack, and means for driving said pinion, and means to control the operation of said mechanism to start and stop the iron at will at any point within its range of travel.
14. In an ironing machine, the combination of a frame, an ironing table, a carriage mounted to reciprocate in the frame, a flat-iron mounted on and to reciprocate with said carriage, mechanism for reciprocating the carriage comprising a stationary rack, a pinion mounted on the carriage and engaging the rack, and reverse gears for driving said pinion, means for driving said gears and means to control the operation of said mechanism to start and stop the iron at will at any point within its range of travel.
15. In an ironing machine, the combination of a frame, an ironing table, a carriage mounted to reciprocate and vertically movable in the frame, a flat-iron mounted on and to reciprocate with said carriage, mechanism for reciprocating the carriage comprising a stationary rack, a pinion mounted on the carriage and engaging the rack, reverse gears for driving said pinion, and means for driving said gears, means to lift the carriage, and means to control the operation of said mechanism to start and stop the iron at will at any point within its range of travel.
16. In an ironing machine, the combination of a frame, an ironing table, a carriage mounted to reciprocate in the frame, a flat-iron mounted on and to reciprocate with said carriage, mechanism mounted on the carriage for reciprocating the carriage comprising a motor, a stationary rack, a pinion mounted on the carriage and engaging the rack, and reverse gears connected to be driven by the motor and for driving said pinion, and means to control the operation of said mechanism to start and stop the iron at will at any point within its range of travel.
17. In an ironing machine, the combination of a frame, an ironing table, a carriage mounted to reciprocate and to swing vertically in the frame, a flat-iron mounted on and to reciprocate with said carriage, mechanism for reciprocating the carriage comprising reversible gearing mounted on and to reciprocate with the carriage, a pinion driven by said gearing, a stationary rack engaged by the pinion, and a motor connected to drive the reversible gearing, and means mounted on the carriage to control said gearing to start and stop the iron at will at any point within its range of travel.
18. In an ironing machine, the combination of a frame, an ironing table, a carriage mounted to reciprocate in the frame, a flat-iron mounted on and to reciprocate with said carriage, mechanism for reciprocating the carriage comprising reversible gearing mounted on and to reciprocate with the carriage, a pinion driven by said gearing and a rack engaged by the pinion, and means mounted on the carriage to control said gearing to start and stop the iron at will at any point within its range of travel, comprising a clutch-collar, and a handle for shifting said collar.
19. In an ironing machine, the combination of a frame, an ironing table, a carriage mounted to reciprocate in the frame, a flat-iron mounted on and to reciprocate with said carriage, reversible gearing mounted on and to reciprocate with the carriage, means driven by the gearing for reciprocating the carriage, a motor mounted on the carriage for driving said gearing, and means mounted on the carriage to control said gearing to start and stop the iron at will at any point within its range of travel.
20. In an ironing machine, the combination of a frame, an ironing table, a carriage mounted to reciprocate and to swing vertically in the frame, a flat-iron mounted on and to reciprocate with said carriage, mechanism for reciprocating the carriage comprising reversible gearing mounted on and to reciprocate with the carriage, a pinion driven by said gearing and a stationary rack engaged by said pinion, means to manually lift the carriage at any point, and means mounted on the carriage to control said gearing to start and stop the iron at will at any point within its range of travel.

Signed at Chicago, Illinois, this 3rd day of March, 1926.
